UNITED STATES PATENT OFFICE.

WILLIAM CHALLIS, OF AMERSHAM COMMON, AND COURTENAY HAROLD W. EDMONDS, OF LONDON, ENGLAND, ASSIGNEES, BY MESNE ASSIGNMENTS, TO THE UNION SWITCH AND SIGNAL COMPANY, OF SWISSVALE, PENNSYLVANIA, A CORPORATION OF PENNSYLVANIA.

LIGHT SIGNAL FOR RAILWAYS AND THE LIKE.

Application filed October 22, 1924, Serial No. 745,120, and in Great Britain January 15, 1924.

Our invention relates to light signals for railways and the like of the kind comprising one or more signal lamps adapted to project a corresponding number of differently colored beams of light in the direction of a train or vehicle moving along the railway track so as to constitute different signal indications.

Signal beams of light of this character are found in practice to be extremely effective for this purpose both in daylight and darkness, but owing to the necessity of utilizing substantially parallel beams in order to produce an effective indication at a considerable distance, it is somewhat difficult under some conditions for the driver of an approaching train or vehicle to observe the signal beam when closely adjacent to its point of origin, that is to say, when the train is at or near the signal lamp itself.

Accordingly, our present invention has for its object to overcome this difficulty by providing a relatively divergent "spot" or auxiliary light beam, so arranged as to be visible at a short distance from and up to the position at which the signal lamp is located.

The invention is illustrated by way of example in the accompanying drawings, of which

Fig. 1 is a sectional view of a lamp fitting for a "spot" or auxiliary light beam, the fitting being adapted to be mounted on the hood of the lamp emitting the main signal beam.

Figs. 2 and 3 are views of the fitting for the auxiliary beam as seen from the front of the hood and from the rear of the fitting respectively.

Fig. 4 is a view in side elevation of a portion of the lantern or housing for the main signal beam provided with a fitting embodying our invention.

Referring now first to Figs. 1, 2 and 3, the hood of the lamp emitting the main signal beam is indicated at 1, the fitting for the auxiliary beam comprising a conical base 2 adapted to be secured to the hood 1 by means of bolts as indicated at 3. The outer end or head of the base 2 is provided with a cover ring 4 secured to the base by means of bolts 5, the internal edge of the cover ring 4 and the corresponding aperture within

the head of the base 2 being of spherical form to accommodate a corresponding spherical projection 6, formed at one end of a lamp tube 7. The spherical end of the lamp tube 7 is provided with a conical bushing 8 screw-threaded to the end of the lamp tube 7, the inner end of the bushing 8 being provided with a lens 9 secured by means of the usual wire ring 10. A perforated internal partition 11 in the lamp tube 7 serves to support a lamp holder 12 secured to the partition 11 by means of the shade rings 13 of the lamp holder, the outer end of the lamp tube 7 being closed by means of a hollow plug 14 which is slotted and provided with clamping lugs 15 for the purpose of securing a cable, not shown, containing the conductors leading to the lamp holder 12.

It will be seen that by loosening the bolts 5 of the cover ring 4 the lamp tube 7 may be adjusted so that its axis is inclined to the hood at any desired angle and the auxiliary beam of light emitted from a lamp mounted in the lamp holder 12 can thus be directed as desired relative to the direction of the main signal beam. The lens 9 is preferably of such focus and the lamp tube 7 is so adjusted that the angle of the auxiliary divergent beam extends from a direction at right angles to the track through an angle of approximately 45° towards the direction of the main signal beam. The supply of current to the lamp holder 12 for the lamp of the auxiliary beam is arranged to be controlled in accordance with the supply of current to the corresponding signal lamp or the main beam, and preferably the lens 9 is arranged to be of the same color as the signal lens of the main beam with which the auxiliary beam is associated.

Referring now to Fig. 4 the lantern or housing of the signal is indicated at 16 and is provided with a number of signal lenses for the different signal beams, the upper one of these signal lenses being indicated at 17, and a part of the next lower lens at 18. A hood 1 surrounds the upper part of the signal lenses 17, 18 and the base of a fitting embodying our invention is attached, in the manner previously described, to the hood 1 associated with lens 17, the parts being so adjusted that the beam transmitted from tube 7 is projected in the desired direction.

It will be understood that if desired each of the signal beams emitted from the same housing or lantern 16 may be provided with a fitting, so that a separate auxiliary beam 5 is provided for each main beam, in which case the color of the auxiliary beam is arranged to be the same as that of the main beam, the color of the disc or lens 9 (Fig. 1) being, for instance, the same color as the 10 signal lens 17.

Our invention is evidently not limited to the particular constructions or arrangements above described and illustrated which may be varied as required to meet particular 15 conditions.

Having now particularly described and ascertained the nature of our said invention and in what manner the same is to be performed, we declare that what we claim is:

20 1. In combination with a light signal for projecting a main beam of light and comprising a hood, a hollow base attached to said hood, a cover ring, a cylindrical tube having a semi-spherical projection formed

on one end, means for clamping said projection between said base and said ring to hold the tube in adjusted position with respect to the base, a lens covering said one end of the tube and located in the base member, and a light source in the tube for projecting an auxiliary beam of light from said lens at an angle with said main beam. 25

2. In combination with a light signal for projecting a main beam of light and comprising a hood, a hollow base attached to 30 said hood, a cylindrical tube having one end supported by and extending into such base, a lens covering such one end, an apertured transversely extending partition in said tube, and a threaded lamp holder in the 35 aperture of said partition and provided with rings whereby the lamp holder may be clamped to the partition. 40

In testimony whereof we affix our signatures.

WILLIAM CHALLIS.
COURTENAY HAROLD W. EDMONDS.
